TELESCOPE MOUNT FOR FIREARMS

Frederick L. Humeston, Hamden, Conn., assignor,
by mesne assignments, to Western Cartridge
Company, a corporation of Delaware

Application August 1, 1938, Serial No. 222,319

5 Claims. (Cl. 33—50)

This invention relates to telescope-mounts for firearms and more particularly to that type of telescope-mounts whereby the degree of vertical or horizontal adjustment or variations in such adjustment may be determined visually or by the sense of touch.

One of the objects of the present invention is to provide an improved telescope-mount for firearms which is inexpensive to make; effective in use; and which is readily manipulated for mounting a telescope on and demounting said telescope from a firearm.

Another object of the invention is to provide an improved construction and arrangement of parts in a telescope-mount for firearms whereby a compact assembly of a relatively-small number of parts of simple form may be utilized to facilitate the manufacture and assembly of the said parts; to render them more durable; and to provide a device of this character which is substantially dust-proof, weatherproof, and not likely to get out of order.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken view in side elevation of an embodied form of the present invention according to which a telescope-mount is provided for adjustably mounting the telescope on the barrel of a firearm;

Fig. 2 is a transverse sectional view taken on the line 2—2 of Fig. 1;

Fig. 3 is a central vertical longitudinal sectional view on an enlarged scale and taken on the line 3—3 of Fig. 2;

Fig. 4 is a horizontal sectional view taken on the line 4—4 of Fig. 3;

Fig. 5 is a view partly in side elevation and partly in vertical section of one of the adjusting-units detached;

Fig. 6 is a detached perspective view of one of the detent-members before its assembly in the adjusting-unit;

Fig. 7 is a top plan view of the detent-post;

Fig. 8 is a view of the detent-post partly in side elevation and partly in vertical axial section; and

Fig. 9 is a detached perspective view of a fixed

sleeve-member which forms a portion of the outer wall of a closed detent-housing chamber.

According to the embodied form of the invention selected to illustrate the present invention, a telescope-receiving frame generally designated by the reference character 10, comprises oppositely-arranged arms 11 and 12 which are deflected inwardly each toward the other at their lower ends to form clamping-jaws 13 and 14 of suitable construction and arrangement to be rigidly clamped to the dovetailed upper end 15 of a suitable block-like support 16 which, if desired, may be secured by screws 17 to the barrel 18 of a rifle or other firearm. A clamping-screw 19 having a knurled head 20 is rotatable in a journaling-aperture 21 formed in a struck-up protuberance 22 in the arm 11 and at its other end 23 has a threaded connection with a threaded aperture 24 in a struck-up protuberance 25 formed in the arm 12.

As shown to the best advantage in Fig. 2, a telescope 26 extends through the opening in the telescope-receiving frame 10 and is supportably engaged by a central intermediate portion 27 of a spring-wire cradle designated generally by the reference character 28. The central intermediate portion 27 of the cradle 28 extends rearwardly under the telescope 26 above the clamping-screw 19 and is connected by laterally-spaced coiled spring portions 29—29 with rearwardly extending terminal-branches 30—30 of the cradle. The said terminal branches 30—30 rest upon the clamping-screw 19 and are anchored at 31—31 in the clamping-jaws 13 and 14 respectively.

By means of the above-described construction and arrangement of parts, the telescope 26 is maintained in seated engagement with the inner end of a vertical adjusting-screw 32 whereby, in the manner to be presently described, the adjustment of the telescope in the vertical plane of the barrel 18 is effected. As shown particularly well in Fig. 3, a tubular detent-post generally designated by the reference character 33, is provided with a tubular neck 34 fitting into a socket-opening 35 formed in the telescope receiving frame 10, the said neck 34 being riveted in position at 36 at the inner face of the telescope-receiving frame 10. Immediately above and spaced from the upper surface of the frame 10, the detent-post 33 is provided with an annular enlargement or shoulder 37 between which and the said frame is clamped the inwardly-deflected annular flange 38 of a cylindrical sleeve 39 extending around and spaced outwardly from an upwardly-extending tubular shell 40 of the detent-

post 33. The said tubular shell 40 is provided exteriorly with longitudinal grooves or notches 41 and interiorly with screw-threads 42.

In connection with a telescope-receiving frame 5 such as that referred to above for adjustably mounting telescopes on firearms, the present invention is concerned with an improved construction and arrangement of parts in and related to a vertically-acting adjusting-unit for determining, for example, the proper elevation of a gun for a given range of fire; as well as to a horizontally-acting adjusting-unit suitable for use in determining, for example, the amount of sight-deflection necessary to compensate for wind-displacement of a missile fired from the said gun. Inasmuch as the vertically-acting and horizontally-acting adjusting-units are substantially similar in construction and are associated with operating connections which are arranged and function in the same manner in both instances, a description of one of these adjusting devices with its associated parts will serve for both.

As shown particularly well in Fig. 3, an adjusting-unit which is designated generally by the reference character 43, comprises in addition to the adjusting-screw 32, a cup-shaped cap designated generally by the reference character 44 and a detent-member which is designated generally by the reference character 45. Presented upwardly from the upper end of the adjusting-screw 32, is an integral rivet 46. As shown to the best advantage in Fig. 6, the detent-member 45 is provided with a central hole 47 formed in the flat disk-like top-wall 48 thereof and snugly fitting over the rivet 46 at the top of the said adjusting-screw 32.

The detent-member 45 is provided with a circular marginal flange 49 from which depends on one side of the central hole 47, a detent-finger 50 which conforms to the curvature of the circular flange 49 and is provided on its concave inner surface with an inwardly-struck detent-projection 51. Depending from the circular flange 49 on the opposite side of the central hole 47 from the detent-projection 51 is a stabilizing-finger 52 which also conforms to the curvature of the marginal flange 49 and is bent inwardly slightly toward the axis of the adjusting-screw 32 for slidable engagement with the outer surface of the tubular shell 40 during rotational movement of the adjusting-screw 32 accompanied by the clicking engagement of the detent-projection 51 of the detent-finger 50 with the grooves or notches 41 in the outer wall of tubular shell 40.

The cup-shaped cap 44 comprises a flat disk-like top-wall 53; a cylindrical finger-grip portion 54 which is preferably knurled to facilitate the manipulation of the adjusting-unit 43; and a depending skirt 55 which but slightly clears the outer wall of the sleeve 39 during endwise and rotational displacement of the adjusting-screw 32. The disk-like top-wall 53 of the cap 44 is provided with a central hole 56 which fits snugly over the rivet 46 and is countersunk at its outer end as at 57 to permit the upper end of the said integral rivet 46 to be riveted or headed down therein, for the purpose of uniting the adjusting-screw 32, detent-member 45, and cap 44 into a unitary structure 43 (Fig. 5).

If desired, the lower portion of the bevelled outer surface of the depending-skirt 55 of the cup-shaped cap 44 may be inscribed or otherwise provided with an annular series of longitudinal index-marks 58 for being read in conjunction 75 with a longitudinal index-mark 59 provided upon

the outer surface of the sleeve 39. The extreme inner edge of the depending-skirt 55 of the cup-shaped cap 44 is adapted to sequentially register with a series of transverse index-marks 60 leading laterally from the longitudinal index-mark 59, just above referred to, and spaced a distance from each other corresponding to the pitch of the threads on the adjusting-screw 32.

It will be understood from the foregoing and by reference to the accompanying drawings that the present invention provides a substantially weatherproof and dust-proof detent-chamber of annular form which is closed at the top by the flat top-wall 48 of the cup-shaped cap 44 and is closed at the bottom by the annular enlargement 37 of the tubular detent-post 33. Around its outer periphery, the detent-chamber, just above referred to, is closed by the telescoping skirt 55 and sleeve 39. Within the said annular detent-chamber thus formed are arranged the interengaging fixed and movable detents comprising, in the instance shown, the detent-projection 51 and the annular series of longitudinal detent-grooves 41 formed in the outer wall of the tubular shell 40 of the detent-post 33.

It will be seen that the construction and arrangement of parts above described provides an exceedingly simple, effective and compact arrangement of fixed and movable detents which interact with each other substantially in a cylindrical chamber concentrically and intermediately arranged with respect to a relatively-smaller cylindrical member and a corresponding relatively-larger cylindrical surface.

Mounted in the arm 12 of the telescope-receiving frame 10 is an adjusting-device like that above described, save that it serves to laterally or horizontally adjust the telescope 26 to permit compensation for the wind-displacement of missiles fired from the gun upon which the telescope 40 is mounted. The adjusting-means just referred to, which is mounted in the arm 12 of the telescope-receiving frame 10 corresponds, as before noted, to the vertically-adjustable means above described, and the parts of the said horizontally-arranged adjusting-means are designated by the same reference characters as those employed first above, save that the additional character "a" has been included therewith.

The telescope 26 is retained in yielding seated engagement with the inner end of the horizontal adjusting-screw 32a by means of a spring-pressed cup-shaped plunger 61 having an inner end-wall 62 bearing against the adjacent portion of the telescope 26. The said cup-shaped plunger 55 61 has reciprocating movement in a reversely-arranged cup-shaped cylinder 63 extending through an opening 64 formed in the arm 11 of the telescope-receiving frame 10. The said cylinder 63 is provided at its inner end with 60 an outwardly-extending stop-flange 65 bearing against the inner face of the arm 11 under the tension of a helical spring 66 jointly housed within the cup-shaped plunger 61 and the cup-shaped cylinder 63, as is shown in Fig. 2. The helical 65 spring 66, just referred to, bears at its inner end against the end-wall 62 of the plunger 61 and at its outer end bears against the end-wall 67 of the cylinder 63, so as to exert a constant but yielding effort to shift the telescope 26 toward 70 and against the inner face of the adjusting-screw 32a.

The invention may be carried out in other specific ways than those herein set forth without departing from the spirit and essential charac- 75

teristics of the invention and the present embodiments are, therefore, to be considered in all respects as illustrative and not restrictive, and all changes coming within the meaning and 5 equivalency range of the appended claims are intended to be embraced therein.

I claim:

1. A telescope-mount for firearms, comprising: 10 a telescope-receiving frame; a tubular detent-post connected to the said frame; an adjustment-screw having a threaded connection with the interior wall of the said tubular detent-post, the said detent-post and adjustment-screw being provided with interengaging detents at the outer 15 peripheral surface of the former; a fixed sleeve concentrically arranged with the said detent-post; and a cup-shaped cap mounted on the adjusting-screw, the said cup-shaped cap being movable rotationally and endwise relatively to 20 the said fixed sleeve and in juxtaposed relation thereto to provide a housing for the said interengaging detents.

2. A telescope-mount for firearms, comprising: 25 a telescope-receiving frame constructed to be attached to a gun; a tubular detent-post mounted in the said frame and provided interiorly with screw-threads and exteriorly with peripheral notches extending longitudinally thereof; an adjustment-screw threaded into the said detent- 30 post, the said adjustment-screw being arranged to have endwise seating engagement with the tubular wall of a telescope extending through the said telescope-receiving frame; a detent-finger mounted on the said adjustment-screw and extending exteriorly of the said detent-post to engage in said peripheral notches during a rotational movement of the said adjusting-screw; a fixed cylindrical sleeve concentrically arranged with the tubular detent-post and in snugly-inter- 35 fitting engagement therewith at the bottom, said sleeve being radially spaced outwardly from the circular path of the said detent-finger; and an adjustment-screw-actuating-cap secured to the said adjusting-screw at the top and having a de- 40 pending skirt telescopically arranged with respect to the outer surface of the fixed cylindrical sleeve and with a slight peripheral clearance therebetween.

3. A telescope-mount for firearms, comprising: 50 a telescope-receiving frame constructed to be attached to a gun; a tubular detent-post provided interiorly with screw-threads and exteriorly with peripheral notches extending longitudinally thereon; a fixed cylindrical sleeve of relatively- 55 larger diameter than the tubular detent-post and concentrically arranged in respect thereto to provide an annular chamber between it and the outer wall of the said detent-post; an adjustment-screw threaded into the said detent-post, the said ad- 60 justment-screw being arranged to be in endwise seating engagement with the tubular wall of a telescope extending through the said telescope-re- 65 ceiving frame; an adjustment-screw-actuating-cap mounted on and enclosing the outer end of said adjustment-screw, the said actuating-cap

being provided with a depending skirt telescopically-arranged with respect to the outer surface of the said fixed cylindrical sleeve and a detent-finger having an upper end portion secured to the said adjustment-screw within the actuating-cap 5 and extending longitudinally within the said annular chamber to engage the peripheral notches in the said detent-post during a rotational movement of the said adjusting-screw.

4. A telescope-mount for firearms, comprising: 10 a telescope-receiving frame constructed to be attached to a gun and provided with an opening therethrough; a tubular detent-member mounted at its inner end in said opening and projecting outwardly from the said frame, said tubular detent-member being provided with longitudinal notches in its outer wall and with a concentrically-mounted sleeve of larger diameter extending therearound and forming a detent-chamber between the said sleeve and the said tubular detent- 15 member; a knurled cap mounted on the outer end of the said adjusting-screw, said knurled cap being provided with a skirt extending around and in contacting engagement with the said tubular sleeve; and a second detent-member having a 20 central disk-like portion interposed between the outer end of the said adjusting-screw and the inner wall of the knurled cap, and having a de- 25 tent-finger extending into said detent-chamber to engage the longitudinal notches in the outer 30 periphery of the tubular detent-member.

5. A telescope-mount for firearms, comprising: 35 a telescope-receiving frame constructed to be attached to a firearm and provided with an opening extending outwardly therethrough; a tubular 40 detent-member mounted at one end in the said opening and provided exteriorly with longitudinally-extending notches; an adjusting-screw threaded into the interior of said tubular detent-member; a tubular sleeve projecting outwardly 45 from the said frame in concentric arrangement with said tubular detent-member, said tubular sleeve having an internal diameter larger than the outside diameter of the said tubular detent-member to form therewith an annular detent-chamber; a second detent-member comprising a central disk-like portion concentrically arranged with and at the outer end of the adjusting-screw, 50 a detent-finger extending therefrom into the said detent-chamber to click with the exterior 55 notches in the periphery of the said tubular detent-member; and a stabilizing-finger extending from the said disk-like portion of the said second detent-member and having a terminal portion thereof in movable engagement with the outer periphery of the said tubular detent-member 60 within the said detent-chamber; and a cup-shaped cap comprising a disk-like top wall concentrically arranged with the adjusting-screw and secured together with the central disk-like portion of the second detent-member to the outer end of said adjusting-screw and a skirt surrounding and telescopically overlapping the said tubular sleeve.

FREDERICK L. HUMESTON.
